UNITED STATES PATENT OFFICE

JOHN FRANCIS O'CONNOR, OF TOLEDO, OHIO, ASSIGNOR TO DOHERTY RESEARCH COMPANY, OF NEW YORK, N. Y., A CORPORATION OF DELAWARE

FURNACE

Application filed February 26, 1921. Serial No. 448,280.

This invention relates to furnaces and, in particular, to furnaces adapted to burn either solid fuel or gas.

In the production and distribution of gas for domestic and miscellaneous industrial uses in cities, there are periods of heavy and light demand on the distributing systems. Such periods occur at various parts of the day and also depend on the day of the week and the state of the weather. For example, the demand on a gas distributing system is ordinarily less on a warm day than on a cold day, and, particularly in the case of a gas producing and distributing company supplying many industrial users, the demand is much less on a Sunday or a holiday than on working days.

It is impossible to produce gas efficiently at rates varying even approximately in accordance with the variations in the demand on the distributing lines. Moreover, especially in cases where the demand varies greatly, it is uneconomical to provide storage for the large amounts of gas which, where production is maintained at a fairly uniform rate, must be accumulated at times of small demand in order to satisfy the increased demand at other times. In view of the above considerations it is important that means should be devised which will utilize economically all or a part of the excess gas which is produced at times of small demand on a gas distributing system, and which will consume little or no gas at times of large demand.

To this end, an object of the invention is to provide an improved furnace which may be operated with gas at times when the demand for gas would otherwise be small, and which at periods of heavy demand may be caused to burn solid fuel and little or no gas.

In the illustrated embodiment of the invention, the furnace is combined with a boiler which may in turn be used for the generation of electrical current. Such a furnace and boiler would preferably be used in a situation where there is a large and fairly uniform demand for power; for example, in the power house of a street railway company.

It has hitherto been proposed to construct furnaces capable of burning either gas or

solid fuel. So far as applicant is aware, however, none of such furnaces has been adapted to burn artificial gas of the type produced in coke ovens. Coke oven gas is widely used in cities for domestic purposes. One of the reasons why prior furnaces have not been adapted to burn such gas is that it has a high flame propagation which causes the combustion of the gas to take place largely in a localized area closely adjacent to the burners and also causes the flame of the gas to flare back in an ordinary burner.

Accordingly, a further object of the invention is to provide means which will be adapted to burn gas of high flame propagation such as coke oven gas and which will be capable of use in a furnace constructed to burn either gas or solid fuel.

An important feature of the invention resides in the provision in connection with a fire chamber in which solid fuel may be burned, of a bridge wall at one side of the fire chamber having a series of gas burner openings and means for separately controlling the supply of gas to the burner openings. In the illustrated construction, the furnace also comprises a rear wall disposed at the opposite side of the bridge wall from the fire chamber and spaced from the bridge wall by a distance such as to enable an operative to pass between the walls in order to control the supply of gas and air to the burner openings.

Other important features of the invention pertain to the devices for burning the gas. Preferably, and as shown, the burners are constituted by hollow blocks of special refractory material, such, for example, as carborundum, arranged to conduct gas into the burner openings at points adjacent to the fire chamber, and means through which air is supplied to the burner openings including a checker-work located in the bridge wall to the rear of the burner openings.

Although the gas burning devices of the invention will be described herein with reference to their use in a furnace for burning solid fuel, for which use they are particularly adapted, it will be evident that they are also capable of use in other relations. It is

intended, therefore, that the scope of the invention shall not be restricted except as required by the claims.

Other objects and features of the invention will appear as the description proceeds and will be pointed out in the claims.

In the accompanying drawings which illustrate a preferred embodiment of the invention;

10 Fig. 1 is a view in sectional elevation of a furnace constructed in accordance with the invention and having a boiler associated with it;

15 Fig. 2 is a sectional view in plan of the furnace bridge wall taken on the line 2—2 of Fig. 3;

20 Fig. 3 is a view of the furnace bridge wall in elevation and partly in section on the line 3—3 of Fig. 2;

25 Fig. 4 illustrates a portion of one of the pipes for supplying gas to the gas burners;

Fig. 5 is a fragmentary view of the devices for controlling the supply of air to one of the burner openings in the bridge wall; and

30 Fig. 6 is a perspective view of one of the gas burners.

In the illustrated construction, the fire chamber 2 intervenes between a front wall 4 and a bridge wall 6 and is provided at its bottom with a grate 8 on which coal or other solid fuel may be burned. Coal is delivered upon the grate 8 from a hopper 10 by means of plungers (not shown) operating between the sections of the grate, and the air 35 for supporting the combustion of the coal is introduced into the space below the grate 8 through a pipe 12.

Extending across the fire chamber 2 and the bridge wall 6 is a group of water tubes 14 supported at one end on the front wall 4 and at the other end on a rear wall 16 disposed substantially parallel to the bridge wall 6. The tubes 14 communicate at their ends with headers 18 and 20 located above the walls 4 and 16 respectively. The headers 18 and 20 are in turn connected to a water and steam drum 22 by pipes 24 and 26. Water is maintained in the drum 22 at about the level of the pipe 24, and circulation is maintained in the boiler system thus formed from the drum 22 through pipe 26, header 20, tubes 14, header 18, and thence through the pipe 24 back to the drum 22. The water, while passing through the tubes 14, is wholly or partially converted into steam which issues from the drum 22 through a pipe 28.

The hot gases resulting from the combustion in the fire chamber 2 rise about the tubes 14 and are caused to pass first upwardly around all of the tubes by a baffle 30 upstanding from the bridge wall 6 and then downwardly by a baffle 32 depending from the top wall of the furnace. The gases then flow upwardly again to a flue 34 which con-

ducts them into a breaching 36 leading to an economizer 38.

The parts thus far described constitute in themselves no part of the present invention. A more complete description of them is, therefore, deemed unnecessary.

In order to adapt the furnace to burn gas in place of or in addition to solid fuel when gas can be advantageously procured, the bridge wall 6 is formed with burner openings 40 located in a horizontal row above the adjacent end of the grate 8. As shown, the openings 40 (Fig. 2) are of rectangular form, and each of them is provided with three gas burners, of which two are located on one side of the burner opening and the third on the opposite side. Manifestly, however, the number and arrangement of the gas burners in the burner openings 40 of the bridge wall 6 may be varied without departing from the scope of the invention so long as a sufficient number of vertically spaced burner are provided to distribute the gas combustion uniformly throughout the openings 40.

On account of the high flame propagation of coke oven gas, when such gas is burned in the furnace, the combustion of the gas is practically complete before it passes from the fire chamber 2, so that substantially no combustion takes place in the space occupied by the water tubes 14.

Moreover, the greater part of the combustion takes place close to the burner openings in the bridge wall 6. The front wall 4 and the greater part of the bridge wall 6 of the furnace are composed of refractory material such, for example, as high grade fire brick. In order, however, to enable the bridge wall without disintegration to sustain the intense heat generated adjacent to the burner openings, the face of the wall on the side toward the fire chamber 2 is lined with blocks made from carborundum or other material of special refractory quality. In the illustrated construction, the lining blocks are denoted by heavy lines where they appear in section on the drawings. These blocks cover the bridge wall 6 between the openings 40 as indicated at 42, (Fig. 2) and are also located above and below the openings 40 as shown at 44 and 46 (Fig. 1). The vertical sides of the openings 40 are covered with lining blocks in zones extending for some distance back from the fire chamber 2. The blocks designated 48 and 50 in Fig. 1 are special refractories, as are also the blocks which intervene between them along the side of the burner opening.

The gas burners are preferably arranged to deliver gas to the openings 40 at points adjacent to the fire chamber 2. When coke oven gas is used in the furnace, the flame of the burning gas, due to its high flame propagation extends back into substantial contact

with the burners. As a consequence, burners of usual construction, for example, metal burners, cannot be used in a furnace for burning such gas in large quantities since the burners would quickly become overheated and burned out. The burners 52 of this invention are particularly designed for use in burning gases of high flame propagation, and, to this end, they are formed of blocks 10 of carborundum or other special refractory material. As shown, each of the burners 52 is formed with a passage for gas having a straight main portion 54 leading from one of its ends to a point adjacent to its other end and a short laterally deflected portion 56 leading from the portion 54 to one side of the block and opening out of the side of the block at a point adjacent to its other end. The blocks 52 are set into the bridge wall 6 around the openings 40, and are so arranged that the sides of the blocks containing the laterally deflected portions 56 of the gas passages form part of the inner surfaces of the burner openings 40. The ends of the blocks 25 52 adjacent to the portions 56 of the gas passages are spaced from the fire chamber 2 by lining blocks 58 so that the burner blocks 52 are caused to deliver gas directly to the burner openings 40 of the bridge wall 30 6 at points spaced by a short distance from the fire chamber 2.

The arrangement of the gas burner blocks 52 relatively to the lining blocks 48, 50 and 58 and the blocks intervening between them 35 is such that gas is delivered to the openings 40 within the zones faced with the lining blocks so that the main body of the bridge wall is protected from the flame of the burning gas. In the illustrated construction, the 40 gas burns in the fire chamber 2 and the adjacent ends of the openings 40 of the bridge wall. The flame of the gas extends back in the openings 40 substantially to the plane of the mouths of the portions 56 of the 45 passages of the burners 52.

Gas is supplied to the burners 52 from a conduit 60 located in the space between the bridge wall 6 and the rear wall 16.

It is found in the use of gas furnaces that greater heating value in relation to the amount of gas consumed is obtained by shutting off some of the burners when it is desired to reduce the heat of the furnace, than by decreasing the supply of gas to all of them. In the illustrated construction, in order that the supply of gas may be shut off from some of the burners while the other burners are operated at rates which allow the greatest degree of efficiency to be attained, the burners 52 are supplied from the conduit 60 by individual pipes 62, each of which is provided with a valve 64, and the rear wall 16 of the furnace is located at a distance from the bridge wall sufficient to allow an opera-

tive to pass between them, thus affording access to the valves 64 so that the supply of gas to the burner openings can be separately and independently controlled. The valves 64 are located in vertical portions 65 of the pipes which form angles with horizontal portions 66. The portions 66 of the pipes in turn have their ends sealed into the passages 54 of the burners 52 as shown in Fig. 6. The end wall of the space between the bridge wall 6 and the rear wall 16 may be provided with a door 67, and a roof 68 intervening between the walls 6 and 16 prevents soot from being deposited between the walls.

The introduction of air to the burner openings 40 is regulated by doors 69 hinged vertically on rods 70 (Fig. 2). The doors 69 may be retained in any desired position of adjustment by latches 72 co-acting with serrations 74 (Fig. 5) on a semi-circular segment bar 76 located at the bottom of each of the burner openings 40. To the end that a plentiful supply of air may be afforded to the burner openings 40 and the space between the walls maintained relatively cool, the rear wall 16 is formed so that a large part of its area is open. In the illustrated construction, this is effected by providing it with large openings 78 (Figs. 2 and 3).

Burners of the type heretofore employed in gas furnaces cannot practically be used for burning coke oven gas for the further reason that, due to its high flame propagation, the flame of the gas would flare back in the burners. The flaring back of the flame can be largely avoided in the use of the present construction by reason of the ease and precision with which the supply of gas and air to the burners can be regulated by the valves 64 and hinged doors 69. In spite, however, of such capacity of regulation, some difficulty was at first experienced in properly controlling the flame so that it would not flare back. This difficulty was obviated by filling in the burner openings 40 adjacent to the doors 69 with a checkerwork 80 of fire brick, thereby increasing the effective velocity of the air as it reaches the burners. With this construction, the gas is caused to burn in front of the point where it issues from the burners 52.

It is sometimes desirable to cool the burners 52 when their use has been discontinued. To this end, means is provided whereby air may be admitted to the pipes 62 intermediate between the valves 64 and the burners 52. As shown, such means comprises extensions 82 (Fig. 4) projecting upwardly from the horizontal portions 66 of the pipes 62 in line with the vertical portions 65. The extensions 82 are provided at their upper ends with valve casings 84 which are open to the air at 86. The valve casings 84 carry valves 88 which

normally prevent the admission of air to the pipes 62. If, however, it is desired to cool a burner after the valve 64 of its supply pipe has been closed to extinguish the flame at the burner, the valve 88 may be opened to induce flow of air through the burner.

The invention having been fully described, what is claimed as new and is desired to be secured by Letters Patent of the United States is:

1. In a furnace, a fire chamber having a wall formed to provide a series of openings uniformly spaced horizontally across the width of the chamber through which air may enter into said chamber, a plurality of vertically spaced burners mounted in each of said openings, means for individually controlling the respective burners from the outside of said chamber, and means for controlling the flow of air through the individual openings.

2. In a furnace, a member having a gas burner opening, hollow refractory blocks set in the member about the opening and operating as burners to conduct gas directly to the opening at points adjacent to one end of the opening, means for supplying gas to the blocks, and checkerwork adjacent to the other end of the opening for increasing the effective inlet velocity of the air through the opening to prevent the flame of the burning gas from back-firing.

3. In a furnace, a member having a gas burner opening, means for causing gas to be burned adjacent to one end of the opening, checkerwork adjacent to the other end of the opening for increasing the effective inlet velocity of the air through the opening to prevent the flame of the burning gas from back-firing, and hinged doors at the last-mentioned end of the opening for adjustably controlling the supply of air to the opening.

4. In a furnace, a fire-chamber having a wall formed to provide a series of openings spaced horizontally and through which air may enter into said chamber, a plurality of vertically spaced gas conduits adapted to deliver combustible gas into each of said openings, means whereby the effective velocity of air is increased near the point at which it enters each of said openings, means for individually controlling the respective gas delivery conduits from the outside of said chamber, and means for controlling the flow of air through the individual openings.

5. In a furnace, a wall having a plurality of burner openings therein, a plurality of ports for delivering gas to each of said openings, means whereby air is supplied to said openings for supporting combustion, individual pipes for supplying gas to said ports, control valves in said pipes, and valved connections to each pipe in the port side of said valves whereby the suction in the furnace may draw cooling air through said burners

when the corresponding control valves are closed and the second mentioned valves are opened.

6. In a furnace, a refractory wall forming one side of a fire chamber for said furnace, a series of burner conduits extending through said wall and adapted to project flame into said chamber, a higher refractory lining in the outlet ends of said conduits and on the chamber side of said wall adjacent said conduits, a plurality of combustion gas outlet ports in the inner surface of each conduit in the higher refractory lining therein, and adjustable closure means for each conduit at the end remote from said chamber for admitting air for combustion. 75

7. In a furnace structure, a burner for supplying hot products of combustion thereto, which comprises a conduit opening into said furnace through which burning gases are adapted to be delivered, means for admitting air to said conduit, means for introducing combustible gas into the said conduit at a plurality of points through ports in the inner surface of said conduit near the discharge end thereof, said last mentioned means comprising refractory blocks having gas passages therein, said blocks being mounted in the wall of said conduit, and means for conducting combustible gas to the passages in said blocks. 85

8. A furnace, comprising refractory walls forming a fire chamber, a channel through one of said walls comprising a burner for projecting a flame into said chamber, gas delivery ports in the inner surface of said channel near the channel outlet to said chamber, means for delivering combustible gas to said ports, and an adjustable closure for the end of said channel remote from said chamber for the admission and control of air for burning the gas introduced near the outlet end of said channel. 100

In testimony whereof I affix my signature.
